(57) CLAIM

The ornamental design for a fishing bait threader, as shown and described.

DESCRIPTION

FIG. 1 is a perspective view of the sleeve of the fishing bait threader;

FIG. 2 is a left side view of the sleeve thereof;

FIG. 3 is a bottom view of the sleeve thereof;

FIG. 4 is a right side view of the sleeve thereof;

FIG. 5 is a top view of the sleeve thereof;

FIG. 6 is a front view of the sleeve thereof;

FIG. 7 is a back view of the sleeve thereof;

FIG. 8 is a perspective view of the hook thereof;

FIG. 9 is a left side view of the hook thereof;

FIG. 10 is a bottom view of the hook thereof;

FIG. 11 is a right side view of the hook thereof;

FIG. 12 is a top view of the hook thereof;

FIG. 13 is a front view of the hook thereof;

FIG. 14 is a back view of the hook thereof;

FIG. 15 is a perspective view of the sleeve in place over the hook; and,

FIG. 16 is a perspective view of the sleeve pulled back from the end of the hook.
